N. P. CHIPMAN AND WILLIAM T. COLLINS, OF WASHINGTON, DISTRICT OF COLUMBIA.

Design No. 3,298, dated December 29, 1868.

DESIGN FOR A BADGE.

The Schedule referred to in these Letters Patent and making part of the same.

To all whom it may concern:

Be it known that we, N. P. CHIPMAN and WILLIAM T. COLLINS, of Washington, in the county of Washington, and District of Columbia, have originated and designed a new Badge for the Grand Army of the Republic; and we do hereby declare that the following is a full, clear, and exact description of the construction and operation of the same, reference being had to the annexed drawings, making a part of this specification.

What we claim as our invention, and desire to secure by Letters Patent, is—

The design of a badge for the Grand Army of the Republic, herein set forth and shown.

In testimony that we claim the above, we have hereunto subscribed our names, in the presence of two witnesses.

N. P. CHIPMAN.
WM. T. COLLINS.
